UNITED STATES PATENT OFFICE.

MZL FULLER, OF BIRMINGHAM, ALABAMA, ASSIGNOR OF ONE-HALF TO A. L. FULLER-WIDER AND F. G. McCONNELL.

SHIPPING-CARRIER FOR PHONOGRAPH-RECORDS.

1,121,239.

Specification of Letters Patent. Patented Dec. 15, 1914.

Application filed February 19, 1913. Serial No. 749,479.

To all whom it may concern:

Be it known that I, MZL FULLER, a citizen of the United States of America, residing at Birmingham, in the county of 5 Jefferson and State of Alabama, have invented certain new and useful Improvements in Shipping-Carriers for Phonograph-Records, of which the following is a specification.

10 My invention relates to improved means for the shipment of phonograph disk records or record blanks, especially such as are made according to an invention of mine of light and pliable material, sufficiently small 5 and light to be sent in a post-card or letter container.

One object of my invention is to design a mailing carrier which will contain, hold and protect the small, light, pliable type of record.

Inasmuch as all records are provided with a central aperture by means of which they are centered and held upon the rotating turn-table of the phonograph, I take advantage of this as a means for inserting through the phonograph records a retainer which, in the case of the mailing carrier or post-card, may be of an ordinary split paper fastener that is passed through the opening in the 30 record and through the post-card or carrier and has its free ends bent to firmly hold the record in position.

The split ends of the fastener are passed through the post card backing and through 35 the center opening in the record and then are bent down against the record to hold it firmly in the socket. The fastener holds the grooved face of the record firmly against the bottom of the socket and will cause it to be 40 transported safely and at a minimum cost both for postage and package, it being understood that the essential object of my invention is to devise a means, so simple and inexpensive in its nature, that it will enable 45 small records to be handled at post card stands, where an inexpensive machine for making, or reproducing from, the records can be installed and one can send as a corre-

spondence novelty a record which will deliver its message in the sender's voice.

My invention comprises the details of construction and arrangement of parts which, in their preferred embodiment, are illustrated in the accompanying drawings, in which:—

Figures 1 and 2 are front and reverse views of a post-card with my light pliable record inserted therein. Figs. 3 and 4 are respectively back and front views of the light record. Fig. 5 is a cross-sectional view 6 on the line A—A of Fig. 2.

Similar reference numerals refer to similar parts throughout the drawings.

In the embodiment of my invention illustrated in Figs. 1 to 5, I show an ordinary 6 type of post-card 1 which is suitably attached to cardboard or stiff backing 2 in which is cut out a circular countersunk socket 3. A light pliable disk record blank formed of any suitable material 4 is illustrated in Figs. 3 and 4 and has a squared central opening 5. The record face of the disk is adapted to be turned against the front 1 of the card and a paper fastener 6 is passed through the card 1 and opening 5 in the disk 7 and its ends are bent outwardly so as to lap over and engage the record, as shown more clearly in Fig. 5. The back of the record, as shown in Fig. 2, may be provided with spaces suitably marked to receive data pertaining to the time, place and origin of the record, its name, etc. The record, as thus firmly held in the carrier, will not work loose and will have its grooved face protected and can be shipped at a minimum expense 8 through the mails. The record, as shown in Fig. 5, has less thickness than the backing 2, the object of this being that the split ends of the fastener 6 can be forced down against the back of the record to hold it fully protected in position in the countersunk socket.

Having thus described my invention, what I claim as new and desire to secure by Letters Patent, is:—

A correspondence novelty comprising in 95 combination a miniature phonograph record

disk having a center opening, a stiff board having a circular socket therein adapted to receive said record disk, a post card backing for said board, and a split metal fastener having its split end inserted through the post card backing and through the central opening in said record disk, the split ends of the fastener being bent down against the back of the disk to hold it firmly seated in said

socket, and said disk being of less thickness than the depth of the socket, substantially as described.

In testimony whereof I affix my signature in presence of two witnesses.

MZL FULLER.
